UNITED STATES PATENT OFFICE.

WILHO A. KOSKEN, OF BOSTON, MASSACHUSETTS, ASSIGNOR TO STEADYLITE MOTION PICTURE MACHINE CORPORATION, OF NEW YORK, N. Y., A CORPORATION OF NEW YORK.

EXPANSIBLE PULLEY OR THE LIKE.

Application filed March 30, 1917, Serial No. 582,822. Renewed August 18, 1923.

My invention relates to expandible pulleys or the like and has for its primary object to provide improved means for adjusting the size of a wheel or pulley of this character while it is moving continuously. One of the objects of the present invention is to provide suitable means for making accurate speed changes of extreme delicacy in a moving picture film while it is running. By 10 the use of my invention which greatly improves the operation of a continuously moving film, it becomes possible to eliminate the perforations on the edges of the film. These perforations have heretofore been considered necessary for imparting the usual intermittent movement to a film and properly spacing the pictures on the film. To eliminate the jerky movements resulting from a non-uniform spacing of the film feeding 15 perforations constitutes another object of my invention, such non-uniformity being caused by warping, contraction or an elongation of the film after it has been perforated and chemically treated. The ever- 20 changing conditions in atmosphere and temperature require corresponding changes in the movements of the film. According to the present invention, suitable means are provided for overcoming all of the above- 25 mentioned difficulties and by means of this invention it is possible to slightly increase or decrease the diameter of the film driving wheel and in this manner to bring successive pictures in frame with corresponding reflectors such as those shown and described 30 in my copending application Serial No. 281,761 filed March 10th, 1919.

In the drawings:

Figure 1 is a combined side elevation and 40 section of film driving mechanism provided with my improvements, the upper portion of the figure being a section on the line A—A, Figure 2;

Figure 2 is a section on the line B—B of 45 Figure 1.

Figure 3 is a transverse section on the line C—C, of figure 4, showing a modified construction of the film driving wheel.

Figure 4 is an axial section of the same 50 on the line D—D of figure 3, parts being shown in elevation;

According to the embodiment of my invention shown in Figures 1 and 2, mechanism for carrying reflectors at a predeter-

mined speed, is driven directly or indirectly by a shaft 1 to which is secured a pinion 2 which meshes with a gear 3 fastened to a revolving wheel 4 bearing in stationary frames 5 and 6. Wheel 4 has a number of radially drilled holes equally spaced. These 60 holes serve as bearings for spokes 7 to which suitably formed rim sections 8 Fig. 1 are riveted. Springs 9 are intended to act toward the axis being reactionary to centrifugal force. The inner ends of these spokes 65 slide on the tapered portion of the pin 10 Fig. 2. Said pin can be actuated lengthwise by turning knob 11 Fig. 2 and the threaded portion of the pin 10 in the stationary frame 70 6 which action will cause radial motion of the spokes by the tapered portion of the pin 10 and so slightly decrease or increase the diameter of the wheel.

On Figs. 1 and 2 is shown a roller 12 which by means of adjustable springs 13 impose 75 the necessary pressure and friction upon the film 14.

In Fig. 3 and Fig. 4 is shown a modified construction of my invention in which I intend to use an endless elastic band 15 on 80 the rim. This construction eliminates springs, makes a very compact construction and gives a smooth surface with maximum tractive effect.

I claim:

1. The combination with a suitable support of a wheel or pulley journaled for rotation in said support, said wheel or pulley comprising radially movable parts, and an adjusting spindle having threaded engagement with the support to permit longitudinal adjustment of the spindle, said spindle including a tapered rim adjusting portion adapted to be normally stationary and having slidable engagement with said radially movable parts which circumferentially traverse the periphery of the tapered portion during rotation of the wheel.

2. In a moving picture machine, a rigid frame, a wheel or pulley journaled in said rigid frame, and comprising radially movable parts, and a shaft or bar threaded in said rigid frame for axial adjustment, said shaft or bar including a tapered portion in slidable engagement with said radially movable parts, said wheel or pulley having a hollow shaft through which said bar or shaft extends, and said frame being provided with

spaced bearings for said hollow shaft and with extension bearings for said adjusting bar or shaft.

3. The combination with a suitable support of a wheel or pulley journaled for rotation thereon and having radially adjacent rim sections, inwardly extending projections associated with each rim section, a conical portion coaxial with the wheel and engaged by said projections, said conical portion being normally stationary while the wheel revolves, whereby the projections are adapted to traverse the conical portions circumferentially, and means for shifting the conical portion axially to present different portions of the periphery thereof to the traveling projections for the purpose of varying the diameter of the wheel.

4. The combination with a suitable support of a wheel or pulley journaled for rotation thereon and having radially adjacent rim sections, inwardly extending projections associated with each rim section, a conical portion coaxial with the wheel and engaged by said projections, said conical portion being normally stationary while the wheel revolves, whereby the projections are adapted to traverse the conical portion circumferentially, and means for shifting the conical portion axially to present different portions of the periphery thereof to the traveling projections for the purpose of varying the diameter of the wheel, and a continuous annular elastic band embracing the circumference of the wheel to maintain the projections in contact with the conical portion.

5. The combination with a suitable support of a wheel or pulley journaled for rotation thereon and having radially adjacent rim sections, inwardly extending projections associated with each rim section, a conical portion coaxial with the wheel and engaged by said projections, said conical portion being normally stationary while the wheel revolves, whereby the projections are adapted to traverse the conical portions circumferen-

tially, a threaded portion associated with the conical portion and having threaded engagement with the support to effect longitudinal adjustment of the conical portion and present different parts of the periphery thereof to the traveling projections for the purpose of varying the diameter of the wheel.

6. The combination with a suitable support of a wheel or pulley having radially adjacent rim sections, bearing means for journalling the wheel for rotation on the support, and means for radially adjusting said rim sections, said adjusting means being independent of the bearing means, whereby the journalling of the wheel is accomplished independently of the rim adjustment means thereof to keep the adjusting means free from the rotation of the wheel.

7. The combination with a supporting frame, of a wheel or pulley journaled thereon and embodying a plurality of adjacent rim sections, an adjusting spindle having threaded engagement with the frame and provided with a tapered portion, means associated with the adjacent rim sections and bearing against the tapered portion of the spindle, and means for manually rotating the spindle to longitudinally shift its tapered portion for the purpose of varying the diameter of the wheel, said tapered portion being stationary except during such adjustment.

8. The combination with a supporting frame, of a wheel or pulley journaled thereon and embodying a plurality of adjacent rim sections, an adjusting spindle having threaded engagement with the frame and provided with a tapered portion rigid with the remainder of the spindle, means associated with the adjacent rim sections and bearing against the tapered portion of the spindle, and means for manually rotating the spindle to longitudinally shift its tapered portion for the purpose of varying the diameter of the wheel, said tapered portion being stationary except during such adjustment.

WILHO A. KOSKEN.
